BASEMENT WINDOW CONSTRUCTION

Lyle Carnick, Detroit, Mich., assignor to Copco Steel & Engineering Company, Detroit, Mich., a corporation of Michigan

Application April 24, 1956, Serial No. 580,344

7 Claims. (Cl. 20—53)

This invention relates to a basement window construction and more particularly to a tilting, removable metal window sash having locking type lift sash handles at each side element, adapted to seal the sash in its frame at the sill.

This application is a continuation-in-part of my earlier filed copending application Serial No. 402,692 filed January 7, 1954, now Patent No. 2,753,964, issued July 10, 1956, for "Basement Window Construction."

The basement window construction comprises a double contact window sash and frame combination in which the window sash head and side elements are provided with uniplanar flanges adapted to make contact with the window framing at the top and sides. The window is preferably made of metal, is of the bottom tilting type which opens at the top, and is fully removable from its frame upon disengagement of the side positioned locking handles from the keepers on the frame. The locking handles are pivotally mounted on the side elements of the window sash so that they rotate in a plane normal to the plane of the window, i. e. the handles rotate upwardly from a position flush upon the window sash side elements to a position substantially at right angles to the window, so that the window sash can be easily back-tilted and lifted up and out of its frame.

Among the important elements of distinction over the earlier filed application above referred to is the locking cam on the latch handle at each side of the window. This cam is arranged at an angle to the vertical plane of the window when the handle is rotated into its closed window flush position. The angle on the locking cam effects a downward pressure on the window sash bringing the lower edges of the bottom or sill element into double sealing contact with the sill of the frame.

A principal problem in the construction of a suitable and satisfactory basement window is the closure at the sill. Basement windows are generally located close to or at or below grade level. It will be readily understood therefore that rain, snow, sleet, hail and similar elements will be more easily blown into these windows that are close to the ground. Weathering is lost primarily at the sill, the most difficult place to weather seal a window, particularly a basement window. To construct a thoroughly satisfactory basement window, it must have positive weathering features at the sill. That is, the sill of the window sash must seal at the frame sill as nearly perfectly as possible. The instant invention effects the most positive weathering in any basement window known to applicant.

Another distinction is the maintenance of a spacing gap between the webs of the window sash head element and the frame head element so that even though unusual overloading of the frame head should occur, the window sash will move easily out of or into the frame. All too often, through negligence or other causes, the contractor will place an excessive load on the window frame header as he constructs the building at the basement window opening. The spacing gap at the window head permits

2

the frame to deflect slightly without binding the window sash, which can still be opened and closed with ease. Even though deflection in the frame head may occur, double contact between window sash and frame is nevertheless maintained by means of the flanges about the head and side elements of the window sash and frame.

One object of the invention is to provide side locking and lifting handles on a window sash which embody cam type latches that seal the window at the sill under mechanical pressure. Another object is to provide handle latch cams having a slight angle to the vertical plane of the window so that downward pressure of the window against the frame sill is constantly maintained when the handles are positioned in closed position. A further object is to provide handles pivotally mounted on each side of the window sash within the web of the frame, whereby the handles have flat gripping portions that rest flush at the window plane when the handles are in closed position. Another object is to provide slots in the side elements of the window so that double contact of the window in the frame is not modified or reduced, through which slots the pivotally mounted webs of the handles rotate.

These and other objects of the invention and features 25 of construction will become more clearly apparent from the description given below. The terms are used for purposes of description and not of limitation. Referring now to the drawings annexed hereto and made an integral part hereof, showing a preferred embodiment of the invention,

Fig. 1 is a front elevation of the window of this invention.

Fig. 2 is an enlarged vertical sectional view taken substantially on the line 2—2 of Fig. 1.

35 Fig. 3 is an enlarged horizontal sectional view taken substantially on the line 3—3 of Fig. 1.

Fig. 4 is an enlarged fragmentary vertical section of the window sash tilted out of the frame into an open position.

40 Fig. 5 is an enlarged fragmentary horizontal sectional view at the right side of the window sash and frame in Fig. 1, showing the handle in solid lines at closed position and in broken lines at opened position.

Fig. 6 is a front elevational view of the fragmentary portion shown in Fig. 5, with the handle in full opened position.

45 Fig. 7 is an enlarged fragmentary front elevational view of the center bar portion at the window sash and frame header elements, with a portion broken away to more clearly show the gap between window sash and frame header webs.

50 Figs. 8, 9 and 10 are enlarged fragmentary side elevational views showing modifications of the preferred handle latch cam configurations shown in Figs. 2, 5 and 6.

55 As shown in Figs. 1, 2 and 3, the basement window construction of this invention comprises a tilting removable window sash 10 in a frame 12.

Window sash 10 is preferably made of metal and comprises a Z-bar header 14 having a front flange 16, a web 18 and an inside closing flange 20; two Z-bar side elements or stiles 22, each having a front flange 24, a web 26, an inside closing flange 28, and a handle slot 30 in the flange 28 flush with web 26; and a bottom sill member 32 of T-section having a front upper element 34, a front bottom element 36 and a T-bar 38. A center T-section member 40 is fixedly mounted between and conjoined to sash header 14 and sill member 32. The header, side and sill members are conjoined into a rectangular window sash according to practices long known in the window art, these including notching and welding, slotting for end portions that are peened over, and other tech-

niques. The preferred construction embodies one or more of these techniques.

At the sides of window sash 10 are arranged two locking and lifting handles 42 which comprise a grip portion 44, a web 46 at right angles to the plane of portion 44, and a cam 48 normal to web 46. Handle 42 is pivotally mounted on side element web 26, above the center of gravity of the window sash by a pivot pin 50. Thus, when the two handles 42 are grasped and the window sash lifted, the latter will depend in a substantially vertical fashion at the pivot pins. In order that the desired and required double contact be made at the sill, cam 48 is disposed at a slight angle to the vertical plane of the window. It has been found that an angle of approximately 8° provides the requisite camming action which both locks the window sash 10 firmly in frame 12 and forces the window sill member 32 into double contact with the frame sill member 76.

Frame 12, preferably also of metal, comprises the following conjoined elements, a head member 60 of Z-section form having a front depending flange 62, a web 64 and an inside flange 66; two Z-section side members 68, each having a front flange 70, a web 72 and an inside outwardly projecting flange 74; and a bottom sill member 76 having a front depending flange 78, a web 80 and an inside upstanding flange 82.

Double contact of window sash 10 in frame 12 is made at the sill by window sash element 36 bearing on frame web 80 and window sash T-bar 38 bearing on the edge of frame flange 82. On the other three sides of the construction, window sash front flanges 16 and 24 bear against frame front flanges 62 and 70, respectively, and window sash inside flanges 20 and 28 bear against frame inside flanges 66 and 74, respectively, to complete the double contact which provides a tightly closed sealed window construction. It is, of course, well known in the metal window industry that double contact windows provide the best protection against such elements as wind, rain, snow and the like. The basement window construction of this invention likewise meets the high structural standards set by the industry. To applicant's knowledge, there is no metal tiltable, removable basement window embodying a pair of side locking handles on the sash which effect a full double contact seal on all sides of the window when the locking handles are rotated into closed flush aligned position.

In order that the handles 42 operate on window sash 10, the elongated slot 30 is provided in the inside flanges 28 flush with webs 26, so that handle web 46 is rotatable therethrough as the grip portion 44 is moved from its flush closed position, in solid lines in Fig. 2, to its projected open position, in broken lines in the same figure.

To engage handle cam 48 as a keeper, frame side members 68 are provided with a pin 92, preferably round, which is mounted in the frame side member web 72 at a point adjacent and somewhat across from the handle pivot pin 50. It will be observed from the drawing views that the axis of the keeper pin 92 is slightly above and in front of the axis of pivot pin 50. This relationship permits the handle 42 to be rotated into a flush closed position while forcing the window sill member 32 downward into double bearing contact with frame sill member 76, as above described.

Another feature of the construction, which has been described in the above referred to application, provides for tilting and removing window 10 from frame 12. Tilting pivot pins 100 are provided in the window sash sill T-bar 38, and tilting stop pins 102 are provided in the frame side member webs 72. Window glass 104 is mounted in mastic 106 in the conventional manner in window sash 10.

At the head section of the window construction, see Figs. 2 and 7, it is to be noted that a substantial gap 108 is provided between frame head web 64 and window sash head web 18, so that if overloading of the frame should

occur the window sash 10 can nevertheless be tilted inwardly and removed from frame 12. In practice, the gap distance varies from $\frac{1}{8}$ " to $\frac{3}{16}$ " approximately.

Figs. 8, 9 and 10 show modifications of the handle latch cam configuration, being disposed at closed position against cam keeper 92. Fig. 8 shows a straight vertical cam 110 in parallel alignment with the vertical plane of the window. This cam, it was found, did not provide satisfactory closing and sealing at the sill, but permitted upward and downward shifting or travel of sash 10 in frame 12, even though handle cam 110 was closed against keeper 92.

Fig. 9 shows an inwardly curved concave cam 112. The curvature and length of this cam are directly related to the function of the handle. The length of cam 112 should be such that when the handle grip portion is pivoted into full open position, as in Figs. 5 or 6, the upper portion of the cam will have full and ample clearance under keeper 92 to permit free outward tilting of the sash, and conversely to permit free unhindered ingress of the cam when sash 10 is moved into closing position in the frame. Also, the length of cam 112 should be such that it will not make contact, upon pivoting of the handle, with the frame side member outer flanges 70. The lower portion of the curve in cam 112 should be such as to effect a downward pressure of the sash upon the frame sill. These factors in the cam curvature should be considered in the construction of a workable latching handle.

Fig. 10 shows an outwardly curved convex cam 114. The length of this cam should be such that, upon pivoting of the handle, the upper end of the cam will not make contact with the frame side member outer flanges 70. Also, there must be ample clearance between the cam curve and the keeper 92 when the handle is pivoted into open position to permit free and unhindered egress and ingress of the latching mechanism mounted on the sash. In this modification, the upper portion of the cam surface should bear against the keeper 92 to effect a downward pressure of the sash against the frame sill.

At times, for one reason or another, the sills of the frame or sash or both may be bowed. This may occur during installation of the window by the contractor. Or, through sheer happenstance, a small fragment of cement or other material may lodge between the sash sill and the frame sill to raise the sash out of full seated position in the frame. In either event, the handle latching cam 112, Fig. 9, or cam 114, Fig. 10, may be raised to a point where effective engagement with keeper 92 would be difficult or impossible. Therefore, care should be exercised to provide ample clearance between the cam curves of either cam 112 or cam 114 and the keeper 92 to enable the operator to effect proper closing action for the sash in its frame.

It will be understood that lifting of the sash by a bowed sill or other cause may place cam 112, Fig. 9, too high for proper closing, or for the desired downward and horizontal pressures. In the case of cam 114, Fig. 10, lifting of the sash may place the keeper on the lower portion of the cam curve so that the sash is lifted instead of being forced downwardly as desired. In addition, the sash would be held in raised position causing the window head web 18 to come close to or touch the frame head web 64, a result opposite to that desired. The angled straight cam 48 here shown and described was found to operate consistently under all conditions, and it is therefore the preferred construction.

In operation, window sash 10 is titlable inwardly from frame 12 by unlatching cams 48 from keepers 92, through rotation upward of handle grip portions 44. Window sash 10 is freely removable from frame 12 by lifting handles 42 upwardly until tilting pivot pins 100 clear the top edge of frame sill flange 82 and then drawing window sash 10 inwardly past tilt stop pins 102. These features of operation and construction are thoroughly described and disclosed in the above referred to application.

Because the latching mechanism is at the sides of the window construction—sash handles 42 engageable with frame keepers 92—the camming action of cams 48, in addition to effecting a double contact seal at the sill, also causes the sash header web 18 to move downwardly away from frame header web 64, so that the gap opening 108 is positively created. This gap, therefore, provides a means to permit free opening and closing of the window sash even though the frame header may be slightly deflected under load. On the other hand, basement windows which have top latching mechanism should not be deflected at their heads by excessive loads or the latch will become jammed and fail to operate to open or close the window. The instant basement window construction avoids this difficulty, as disclosed.

The instant invention provides, however, the necessary and desirable feature which closes the window sash 10 against the sill of the frame 12, while drawing both sides and head into double contact with the frame. When window 10 is tilted back into closed position in the frame 12, latch cam 48 is substantially horizontal, Figs. 2 and 5, under keeper 92. By rotating handle 42 downwardly, cam 48 is caused to come into contact with keeper 92, sliding upwardly against the keeper while forcing the window sill T-bar 32 into double sealing contact against frame sill 76, as described. Further, the angled cam 48 also draws the window sash side and head member flanges horizontally into firm double sealing contact with the frame side and head member flanges, as described. It is the angled characteristic of the preferred handle cam 48 which achieves these desirable results.

Having described the invention in its simplest terms, it is to be understood that the details of the foregoing specification may be changed and varied in greater or lesser degree without departing from the essence of the invention.

I claim:

1. The combination of a removable window sash, a window frame, and a pair of sash lifting latch handles, said sash having coplanar flange elements on its head and side members adapted to close said sash in said frame, said sash having a T-bar sill member adapted to make weather sealing contact with the sill member of said frame, said handles having flat manual grip portions connected to integrally formed web portions and being pivotally mounted at said web portions on said sash side members in horizontal alignment above the center of gravity of said sash, said handle grip portions adapted to lie flush upon said sash when said handles are pivoted into closed position and to rotate upwardly in a vertical plane normal to the plane of said sash so as to project from said sash when in opened position, and sash locking cams on said handle web portions to latch on locking keeper means mounted on said frame inwardly thereof and above the pivoting axes of said handles, said cams being arranged at a slight acute angle to the vertical plane of said sash, the line of tangency of said cams with respect to said keeper means being inclined downwardly to the inner side of said sash when in fully closed position, said cam engaging and bearing upon said keeper means from below with increasing pressure as said handle is pivoted to closing position to force said sash downwardly into weather sealing contact with said frame sill and simultaneously drawing said sash forwardly into said frame, whereby effective clearance for free opening and closing movement of said sash in said frame is maintained.

2. The combination of a bottom-tilting removable window sash, a window frame, and a pair of sash lifting handles mounted by pivot means at each side of said sash in horizontal alignment above the center of gravity of said sash, said sash and frame each having head, side and sill members in complementary corresponding relationship, whereby said sash members are adapted to seat in closed weather-sealing contact in said frame, said

handles having manual grip portions connected to integrally formed web portions and sash locking cams on said latter portions to engage keeper means on said frame side members inwardly thereof, at a point above the pivoting axes of said handles, and closely adjacent said handle pivot means when said sash is closed in said frame, said cams being straight and flat in form and arranged at a slight acute angle to the vertical plane of said sash, the line of tangency of said cams with respect to said keeper means being inclined downwardly and inwardly of said sash when in full closed and locked position, whereby said cams engage and bear upon said keeper means from below with increasing pressure as said handle is pivoted to closing position to force said sash downwardly into weather-sealing contact with said frame sill and simultaneously to draw said sash forwardly into said frame, and maintaining effective clearance for free opening and closing movement of said sash in said frame.

3. The combination of a bottom-tilting removable window sash, a window frame, and a pair of sash lifting handles mounted by pivot means at each side of said sash in horizontal alignment above the center of gravity of said sash, said sash and frame each having head, side and sill members in complementary corresponding relationship, whereby said sash members are adapted to seat in closed weather-sealing contact in said frame, said handles having manual grip portions connected to integrally formed web portions and sash locking cams on said latter portions to engage keeper means on said frame side members inwardly thereof, at a point above the pivoting axes of said handles, and closely adjacent said handle pivot means when said sash is closed in said frame, each of said cams being curved concavely with respect to said keeper means so that the line of tangency therewith is at a slight acute angle to the vertical plane of said sash and inclined downwardly and inwardly when in fully closed position, and arranged so that the ends of the keeper engaging cam surface when said handle is in full open position lie in a plane below said keeper means to provide free ingress and egress of said sash in said frame, whereby said cams engage and bear upon said keeper means from below with increasing pressure as said handle is pivoted to closing position to force said sash downwardly into weather-sealing contact with said frame sill and simultaneously to draw said sash forwardly into said frame, and maintaining effective clearance for free opening and closing movement of said sash in said frame.

4. The combination of a bottom-tilting removable window sash, a window frame, and a pair of sash lifting handles mounted by pivot means at each side of said sash in horizontal alignment above the center of gravity of said sash, said sash and frame each having head, side and sill members in complementary corresponding relationship, whereby said sash members are adapted to seat in closed weather-sealing contact in said frame, said handles having manual grip portions connected to integrally formed web portions and sash locking cams on said latter portions to engage keeper means on said frame side members inwardly thereof, at a point above the pivoting axes of said handles, and closely adjacent said handle pivot means when said sash is closed in said frame, each of said cams being curved convexly with respect to said keeper means so that the line of tangency therewith is at a slight acute angle to the vertical plane of said sash and inclined downwardly and inwardly when in full closed position, and arranged so that the ends of the keeper engaging cam surface when said handle is in full open position lie in a plane below said keeper means to provide free ingress and egress of said sash in said frame, whereby said cams engage and bear upon said keeper means from below with increasing pressure as said handle is pivoted to closing position to force said sash downwardly into weather-sealing contact with said frame sill and simultaneously to draw said sash forwardly into said frame, and maintaining effective clear-

ance for free opening and closing movement of said sash in said frame.

5. The combination of a removable window sash having stile members and top and bottom rail members, a window frame, and a pair of handles on said sash, said sash having coplanar flange elements on the inner side of each of the top and stile members adapted to engage said frame, said handles having grip portions and web portions connected thereto, said stile flange elements each having a slot, the web portion of said handles passing through the respective slots in said stile flange elements, means pivotally mounting said web portions on said sash at either stile flange element thereof in horizontal alignment above the center line of said sash, locking pins mounted on said frame adjacent and normal to said sash stile members in the plane of said frame and above the pivoting axes of said handles, and sash locking cams on said web portions adapted to engage said locking pins in line contact therewith, said cams being arranged at a slight acute angle to the vertical plane of said sash, the line of tangency of said cams with respect to said locking pins being inclined downwardly to the inner side of said sash when in fully closed posi-

tion, said cams engaging and bearing upon said locking pins from below with increasing pressure as said handle is pivoted to closing position to force said sash downwardly into weather sealing contact with said frame 5 sill and simultaneously drawing said sash forwardly into said frame.

6. The window structure defined in claim 1, and in which said cam is disposed at an angle of approximately 8° to the vertical plane of said sash when said handle 10 is in full closed position.

7. The window structure defined in claim 2, and in which said cam is disposed at an angle of approximately 8° to the vertical plane of said sash when said handle is in full closed position.
